The ornamental design for a skin treatment device, as shown and described.

DESCRIPTION

FIG. 1 is a perspective view of a skin treatment device showing my new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top-side plan view thereof; and,

FIG. 7 is a bottom plan view thereof.

The broken lines, the areas within them, and the areas bounded by both broken lines and solid lines depict portions of the skin treatment device that form no part of the claimed design.
